PLOWSHARE

Walter J. Borst, Moline, Ill., assignor to Deere & Company, Moline, Ill., a corporation of Illinois

Application June 4, 1948, Serial No. 31,114

5 Claims. (Cl. 97—125)

1

The present invention relates generally to agricultural implements and more particularly to plows and other ground working tools.

The object and general nature of the present invention is the provision of a new and improved plowshare which is made of simple parts and in which the cost of construction and assembly is so reduced, as compared with a conventional share, that a plowshare constructed according to the principles of the present invention may be discarded after the same has worn beyond its efficient usefulness, rather than having the shares resharpened at a cost which is greater than the cost of replacement. Further, it is a feature of this invention to provide a share of the disposable type which is adapted to fit and operate efficiently on conventional plow bottoms.

Another important feature of the present invention is the provision of a plowshare which is made of two sections of flat stock welded together at the proper angle. Having the blade section of the plowshare, as well as other parts, made of flat stock lends itself to machine fabrication. For example, the share can be machine polished at substantially less cost than hand grinding and polishing as now required for conventional shares which are not flat. Likewise, other operations, such as beveling etc., now performed wholly or in part by hand, can be done mainly if not entirely by automatic machinery. Still further, another feature of this invention is the provision of a plowshare in which the landside is of the same stock thickness as the blade but is welded to the latter in a position spaced laterally inwardly of the landside edge of the blade, whereby the plowshare is adapted to fit conventional plow bottoms which ordinarily receive plowshares having landside sections thicker than the blade portions thereof.

These and other objects and advantages of the present invention will be apparent to those skilled in the art after a consideration of the following detailed description, taken in conjunction with the accompanying drawings, in which:

Figure 1 is a plan view of a plowshare in which the principles of the present invention have been incorporated;

Figure 2 is a view taken substantially along the line 2—2 of Figure 1 looking directly at the plowshare landside along a line of sight perpendicular to the plane of the landside;

Figure 3 is a view taken generally along the line 3—3 of Figure 2 looking directly at the underside of the plowshare, portions of the latter and the frog of the plow base being broken away;

2

Figure 4 is a fragmentary sectional view taken along the line 4—4 of Figure 2;

Figure 5 is a view similar to Figure 4 showing a modified form of the present invention, wherein the landside edge of the plowshare blade section is sheared perpendicular to the general plane of the blade section;

Figure 6 is an enlarged fragmentary perspective view showing the manner in which the point of the share blade is beveled;

Figure 7 is a view similar to Figure 6, showing the point of the plow clipped off to provide a rounded end at the point of the share, instead of a beveled end as shown in Figure 6;

Figure 8 is a fragmentary perspective view of the plowshare and landside section, showing a modified form of frog-engaging lug which is formed integral with the lug by an extrusion method;

Figure 9 is a sectional view taken along the line 9—9 of Figure 8; and

Figure 10 is a modified form of the present invention.

Referring now to the drawings, the plowshare, which is indicated in its entirety by the reference numeral 1, of the present invention is shown (Figure 3) as mounted on the frog 2 forming a part of a plow base, indicated in its entirety by the reference numeral 3. The plow base 3 may be of conventional construction having the frog 2 provided with a transverse slot 4 formed in the landside wall 5 of the frog 2 to receive a lug or the like carried by the plowshare when the latter is fixed to the frog 2.

The plowshare 1 comprises a flat blade 11 and a generally triangular landside section 12. Both of these parts are made from flat planar stock which, particularly in the case of the blade section 11, makes it possible to perform many, if not all, fabrication operations by machine, such as, for example, to machine, grind and polish the upper or outer face of the blade, whereby substantially all hand grinding and/or polishing is eliminated. The two parts 11 and 12 are preferably of the same thickness and, being flat members, they may easily and quickly be cut by shearing from flat plates.

The landside 12 is secured to the blade 11 in such a position to make an acute angle of approximately 60 degrees. However, the upper edge of the landside 12 is not beveled but is merely sheared at this point, as indicated at 13 in Figures 4 and 5. The two parts 11 and 12 are preferably connected together by welding along the line 15 at the open side of the juncture between

parts 11 and 12. The landward edge of the share blade section 11 may be beveled, as indicated at 17 in Figure 4, so as to provide an edge on the share blade that lies in a plane spaced outwardly or landwardly of the landside 12 and parallel with respect thereto. The amount of overhang at this point is in the nature of one-quarter inch but is sufficient to perform two functions. Firstly, the material of the share blade overhanging the landside 12 makes it possible for the farmer, if he should desire to do so, to keep a sharp edge at the landward end of the plowshare merely by grinding the edge 17 (Figure 4) to bring the same into a plane which is parallel to the general plane of the landside 12.

Secondly, by having the blade overhang the landside as shown in Figures 1-5, the landside staple or lug may be made stronger, as pointed out in detail below. The landside 12 is cut away, as by a notch 21 in Figure 2 or by a diagonal cut 21a in Figure 8, so as to provide a space s to receive the downward and landward portion 22 of the moldboard of the plow bottom. This landward and lowermost portion of the moldboard is customarily thicker than the blade section 11, and therefore the additional space s is required so that the landside 12 would not interfere with the mounting of the share onto a plow bottom in proper relation with the moldboard.

It is not necessary to have the landward edge 17 of the share blade beveled back, as shown in Figure 4, so as to bring the plane of said edge parallel to the plane of the landside 12. Under many, if not all, conditions it may be satisfactory or desirable to have the landward edge 17a (Figure 5) perpendicular to the outer face of the blade 11. In other words, the edge 17a may be formed merely as a shear cut without requiring any grinding off of the plowshare edge. Conversely, if the farmer should desire to have the share blade edge 17a sharper, he may grind the same back to the condition in which the edge is parallel to the plane of the landside 12 as shown in Figure 4.

Referring now to Figure 6, it will be seen that the underface of the plowshare blade 11 is beveled off, as shown at 24, to provide a sharpened leading or soil-separating edge 25. However, in order to avoid a relatively weak and easily deformed forward point (as shown in dotted lines in Figure 6), the point section of the blade 11 is beveled off along the plane indicated at 26 in Figure 6. A modified treatment of the point of the share blade is to clip the same off along a rounded line, as shown at 28 in Figure 7. In both forms the point of the share blade is formed so as to readily enter the ground but has sufficient structural strength to maintain the desired suction and penetration.

Most plowshares are mounted on a frog of the type shown at 3 in Figure 3, namely, one having a slot 4 to receive a lug on the landward portion of the plowshare. According to the principles of the present invention, I provide such a lug in the form of a staple 31 having end sections 32 and 33 that are inserted in openings 34 and 35 formed in the landside 12. By having the latter section offset inwardly of the adjacent edge 17 (or 17a) of the plate section 11, there is sufficient space to form heads 37 on the end sections 32 and 33 of the staple, the heads being shaped somewhat like a button and producing a much more rigid and secure mounting or attachment for the staple 31.

In the form of the invention shown in Figures 75

8 and 9 the riveted button-head type of staple attachment shown in Figure 3 is replaced by a lug 40 which is formed as an integral part of the landside. Preferably, the lug 40 is formed by an extrusion process, using male and female die elements to produce the desired shape. As shown in Figure 8, metal is caused to be displaced laterally inwardly of the landside section 12 so as to form the lug 40 at one side and a recess 41 at the other side, whereby sufficient metal is secured to form the lug 40 of adequate size but without causing undesirable deformation of the landside section 12. Some deformation takes place along the lower edge of the landside 12 to provide a sufficient quantity of metal for the lug 40, as indicated at 43, but this is not objectionable since the parts 11 and 12 are preferably secured together by a welding process along the straight upper edge 44 which is not displaced by the formation of the lug 40.

As also best shown in Figure 8, the landside 12 is preferably made so as to terminate at its forward end 47 a substantial distance d back of the point 26. Since for the distance d the thickness of the share blade remains constant, the share of the present invention possesses the advantages of remaining fairly sharp and retaining its good penetration qualities as the share wears back, as at the point, whereas the conventional lap-forged share tends to "sled runner" which materially reduces the penetration of the share.

In some cases, as when the share is designed for use in particularly difficult conditions, as where numerous stones and the like are encountered, it may be desirable to bring the point 47 of the landside down closer to the point 26 of the share. This construction is shown in Figure 10. However, this does not materially reduce the penetration of the share, even after the point is worn back, for the reason that the landside 12 does not flare out or widen at its point 47a, but is of constant thickness. Hence, there is little tendency for the point to form "sled runners." Further, to increase the penetration of shares of this type after they have worn back at the point, all the farmer has to do is grind off the forwardmost portions of the end 47a of the landside, as shown in dotted lines in Figure 10.

While I have shown and described above the preferred forms of the present invention, it is to be understood that my invention is not to be limited to the particular details shown and described above, but that, in fact, widely different means may be employed in the practice of the broader aspects of my invention.

What I claim, therefore, and desire to secure by Letters Patent is:

1. For use with plow bottoms adapted to receive conventional plowshares in which the landside sections thereof are thicker than the blade sections: a replacement plowshare comprising a substantially flat blade having a diagonal edge at one end thereof, and a flat planar landside of substantially the same thickness as said blade and welded to the blade alongside said edge but spaced inwardly thereof so as to dispose the inner face of the landside substantially in a plane spaced inwardly of the plane of said edge, whereby the plowshare is adapted to fit bottoms constructed to receive conventional plowshares having landside sections thicker than the blade sections, whereby when the replacement plowshare is fixed in position on the bottom, the landward edge of the replacement share lies substantially

in the same alignment with the moldboard as the conventional plowshare, the amount of overhang of the blade over the landside at this point being uniform for substantially the entire length of the landside.

2. For use with plow bottoms adapted to receive conventional plowshares in which the landside sections thereof are thicker than the blade sections: a replacement plowshare comprising a substantially flat blade having a diagonal edge at the end thereof, and a substantially flat landside of substantially the same thickness as said blade and welded to the blade alongside said edge but spaced inwardly thereof so as to dispose the inner face of the landside in a plane spaced inwardly of the plane of said edge a distance such that the plowshare is adapted to fit plow bottoms constructed to receive conventional plowshares having landside sections thicker than the blade sections, whereby, when the replacement plowshare is fixed in position on the plow bottom, the inner edge of the replacement share lies substantially against that portion of the plow bottom against which the inner face of the thicker landside of a conventional plowshare is adapted to bear, and the landward edge of the replacement share lies substantially in the same alignment with the moldboard of the plow bottom as the conventional plowshare, the amount of overhang of the blade over the landside at the landward portion of the plowshare being uniform for substantially the entire length of the landside.

3. For use with plow bottoms adapted to receive conventional plowshares in which the landside sections thereof are thicker than the blade sections: a replacement plowshare comprising a substantially flat blade having a diagonal edge at the end thereof, and a substantially flat landside of substantially the same thickness as said blade and welded to the blade alongside said edge but spaced inwardly thereof so as to dispose the inner face of the landside in a plane spaced inwardly of the plane of said edge a distance such that the plowshare is adapted to fit plow bottoms constructed to receive conventional plowshares having landside sections thicker than the blade sections, whereby, when the replacement plowshare is fixed in position on the plow bottom, the inner edge of the replacement share lies substantially against that portion of the plow bottom against which the inner face of the thicker landside of a conventional plowshare is adapted to bear, and the landward edge of the replacement share lies substantially in the same alignment with the moldboard of the plow bottom as the conventional plowshare, the amount of overhang of the blade over the landside at the landward portion of the plowshare being uniform for substantially the entire length of the landside, the latter having a pair of holes formed therein, and a frog-engaging staple forming a lug on the inner side of said landside and having ends extending through said holes and protruding therefrom at the outer side of said landside, said protruding ends being riveted over to form button-like heads which fixedly lock the staple to the landside but are disposed wholly within the space between the vertical plane passing through the outer face of said landside and the vertical plane passing through the landside edge of the replacement share and the portion of the moldboard aligned therewith, whereby the button-like heads do not contact the furrow wall formed by said landward edge and the aligned moldboard portion.

4. For use with plow bottoms adapted to receive

conventional plowshares in which the landside sections thereof are thicker than the blade sections: a replacement plowshare comprising a substantially flat blade having a diagonal edge at one end thereof, and a substantially flat landside of substantially the same thickness as said blade and fixed to the blade alongside said edge but spaced inwardly thereof so as to dispose the inner face of the landside in a plane spaced inwardly of the plane of said edge a distance such that the plowshare is adapted to fit plow bottoms constructed to receive conventional plowshares having landside sections thicker than the blade sections, whereby, when the replacement plowshare is fixed in position on the plow bottom, the inner edge of the replacement share lies substantially against that portion of the plow bottom against which the inner face of the thicker landside of a conventional plowshare is adapted to bear, and the landward edge of the replacement share lies substantially in the same alignment with the moldboard of the plow bottom as the conventional plowshare, the amount of overhang of the blade over the landside at the landward portion of the plowshare being uniform for substantially the entire length of the landside, the landside of said replacement share being secured to said blade section by a fillet weld, the fillet of which lies beneath the overhang of the blade over the landside but wholly inwardly of the vertical plane passing through the landward edge of the replacement share and the portion of the moldboard aligned therewith.

5. For use with plow bottoms adapted to receive conventional plowshares in which the landside sections thereof are thicker than the blade sections: a replacement plowshare comprising a substantially flat blade having a diagonal edge at the end thereof, and a substantially flat landside of substantially the same thickness as said blade and welded to the blade alongside said edge but spaced inwardly thereof so as to dispose the inner face of the landside in a plane spaced inwardly of the plane of said edge a distance such that the plowshare is adapted to fit plow bottoms constructed to receive conventional plowshares having landside sections thicker than the blade sections, whereby, when the replacement plowshare is fixed in position on the plow bottom, the inner edge of the replacement share lies substantially against that portion of the plow bottom against which the inner face of the thicker landside of a conventional plowshare is adapted to bear, and the landward edge of the replacement share lies substantially in the same alignment with the moldboard of the plow bottom as the conventional plowshare, the amount of overhang of the blade over the landside at the landward portion of the plowshare being uniform for substantially the entire length of the landside, the latter having an opening formed therein, and a frog-engaging member forming a lug on the inner side of said landside and having an end extending through said aperture and protruding therefrom at the other side of said landside, said protruding end being riveted over to form a button-like head which fixedly locks said member to the landside but is disposed wholly within the space between the vertical plane passing through the outer face of said landside and the vertical plane passing through the landside edge of the replacement share and the portion of the moldboard aligned therewith, whereby the button-like head does not contact the furrow wall formed by

said landward edge and the aligned moldboard portion.
